UNITED STATES PATENT OFFICE.

AUGUST L. BETHE, OF HANOVER, GERMANY.

BIT.

No. 804,700.

Specification of Letters Patent.

Patented Nov. 14, 1905.

Application filed April 27, 1905. Serial No. 257,722.

To all whom it may concern:

Be it known that I, AUGUST L. BETHE, a subject of the Emperor of Germany, residing at Hanover, Germany, have invented new and useful Improvements in Bits, of which the following is a specification.

This invention relates to bits, the object of the invention being to provide a simple device of this character which can be used as an ordinary bit or upon fractious or vicious horses to control or check them.

In the drawings accompanying and forming a part of this specification I illustrate a bit involving my invention, which I will describe in detail in the following description, while the novelty of the invention will be covered in the claims succeeding said description.

Referring to the drawings, Figure 1 is a view of the bit, showing the same in its normal position. Fig. 2 is a like view of the bit, showing the manner in which it is used to check an unruly horse. Figs. 3 and 4 are side elevations of the bit in positions corresponding, respectively, with Figs. 1 and 2. In said Figs. 3 and 4 I have shown certain bit-operating devices. Figs. 5 and 6 are views corresponding to Figs. 3 and 4, respectively, and showing the bit applied to a horse and the ordinary mode of its operation and the way in which it operates in controlling a fractious horse, respectively. Fig. 7 is a detail view of a slightly-modified form of frame at the end of the bit proper.

Like characters refer to like parts throughout the different figures of the drawings.

The bit proper (shown in the several figures of the drawings) consists of a divided bar the sections 2 of which are jointed to each other—for example, by means of a pivot. To the opposite ends of the bar or bit proper are pivotally attached in some suitable way (see, for example, Figs. 1 and 2) frames, as 3, which may be of any desirable form. The frame shown is of skeleton construction, although that shown in Fig. 7 is of a little different shape than the type shown in the other figures. The shape of the frame, however, is not one of importance, for it may be of any desirable kind. Each section of the bit proper has a cut-away portion to receive an outwardly-extending arm, as 4, on the complementary section—as indicated in Fig. 1, for example—when the bit is used as a snaffle or the ordinary bit. When the bit is employed for controlling a vicious horse, however, the bar,

consisting of the sections 2, will be flexed, so as to secure the results hereinafter set forth.

A spring is shown at 5, and its terminals are shown as provided with hooks, as 6, to engage the outer ends of the arms or projections 4. When a sufficient stress or pull is put upon the bit proper below the same, as will hereinafter appear, the said bit proper will be first turned and then flexed, and during the latter the spring or flexible connection 5 between the sections 2 will be caused to arch outward and to press against the palate of the horse. When the pressure upon the said bit proper is relieved, the spring acts to return said bit proper into straight or normal condition, as shown clearly in Fig. 1. The spring therefore serves a double function in acting in one case, or when the bit proper is flexed, as a palate-pressing device and in the other to restore said bit proper to its primary relation.

Upon that side of the bit proper opposite the spring 5 is what I will term a "gag" 7, made up of an elongated comparatively flat body having arms extending inward from the same and through longitudinal slots in the sections 2 near their joint. The free ends of these arms are headed or offset to hold the gag in place. When the bit proper is straightened or in its normal relation, the inner face of the body of the gag fits closely against said bit proper, and at this time the offsets at the free ends of the arms of said gag lie in recesses in the projections or arms 4. When the bit proper is turned, it is flexed, as previously indicated, and the spring 5, which connects the sections thereof, is arched against the palate of the horse. Simultaneously with this the gag 7 is caused to press against the tongue or the lower jaw of the animal. In other words, pressure is applied to those surfaces of the mouth of the animal which are most sensitive in order to compel him to open his mouth and effectually check him.

As previously indicated, I can adapt the bit to ordinary uses as well as those necessary to effectually check a vicious horse, which checking I secure in the manner pointed out. It will be remembered that to the outer ends of the bit proper or bar, made up of the sections 2, are connected frames 3. The frame illustrated in Figs. 1 to 6 is practically of loop form. At superposed or vertically-separated points I connect to these frames independent connections, (denoted, respectively,

by 8 and 9,) the opposite ends thereof being joined to rings or their equivalents, as 10, to which the ordinary driving-reins 11 are connected. The lower connection 8 in each case 5 may take the form of a strap of leather or, as illustrated, a chain, while the upper connection is one that is longitudinally yieldable, or, as it is shown, a spring connection. When the bit occupies its ordinary position, the 10 lower connections or chains 8 will be united with the frames 3 beneath the places at which the spring connections 9 are united to said frames—as clearly indicated, for example, in Fig. 3.

15 In the ordinary position, or when the bit is used as an ordinary snaffle-bit, the spring 5 lies adjacent or immediately forward of the gullet, while the gag 7 is immediately behind the front teeth—as shown in Figs. 3 and 5, for 20 example. In this position the bit proper cannot be flexed automatically, for the spring 5 will prevent this. By virtue of the spring connections 9 a light pull can be applied to the reins 11 without turning the bit proper. Upon a strong 25 pull, however, upon the reins the spring connections 9 are longitudinally stretched, so that through the non-yieldable connections 8 the bit proper can be turned in order to cause its flexing when turned and the pressure of the spring 30 5 against the roof of the mouth or palate and the pressure of the gag 7 simultaneously against the tongue or lower jaw. As the horse to be checked lowers his head the bit proper will be flexed nearly at a right angle to the line 35 of the opening of the mouth to cause the said spring 5 and the gag 7 to perform their functions. Said spring and gag are made flat and broad, so as to offer as much surface as possible to the parts which they engage and also 40 prevent the bit from overturning. When the abnormal pull upon the reins is arrested, the spring 5 will return the bit proper to its original position, while the springs 9 by contraction will automatically resume their original 45 relations.

Having thus described my invention, what I claim is—

1. A bit having movably-connected sections mounted for turning movement, and a spring 50 constituting a palate-pressing device, said spring being coöperative with said sections

and the latter being movable to arch the spring.

2. A bit having jointed sections, and a spring constituting a palate-pressing device between 55 and coöperative with the sections, arranged to be arched, to press against the palate of a horse when said bit is rocked.

3. A bit having jointed sections, each provided with an outwardly-extending arm, and 60 a spring connected at its opposite ends with the arms and arranged to be arched upon the flexing of the bit.

4. A bit having jointed sections, a spring constituting a palate-pressing device between 65 connected with the sections and arranged to be arched when the bit is flexed, and a gag for the tongue or lower jaw, connected with said bit.

5. A bit having jointed sections, a spring 70 constituting a palate-pressing device connecting the sections and arranged to be arched when the bit is flexed, and a gag for the tongue or lower jaw of a horse, movably connected with the sections of the bit and arranged to 75 assume an operative position on such flexing.

6. A bit having jointed sections, each provided with an outwardly-extending arm, a spring connected at its opposite ends with the arms and arranged to be arched upon the flexing of the bit, said spring constituting a palate-pressing device, and a gag for the tongue or lower jaw of an animal, having arms at its 80 opposite ends, the sections of the bit having longitudinal slots to receive said arms and for 85 removably uniting the gag with the bit.

7. A bit having jointed sections, a spring between the jointed sections and arranged to be arched on the flexure of the bit, and a gag for the tongue or lower jaw of an animal, 90 having arms at its opposite ends, the sections of the bit having longitudinal slots to receive said arms and for movably uniting the gag with the bit.

In testimony whereof I have hereunto set 95 my hand in presence of two subscribing witnesses.

AUGUST L. BETHE.
